STRAP STRETCHING DEVICE

William C. Childress, Oak Park, Ill., assignor to
 Acme Steel Company, Chicago, Ill., a corpora-
 tion of Illinois

Application October 17, 1935, Serial No. 45,498

13 Claims. (Cl. 254—66)

This invention relates to improvements in strap stretching devices and its purpose is to provide an improved device for use in drawing metal binders taut around boxes, packages or groups of packages 5 preliminary to fastening the overlapping ends thereof together. The principal object of the invention is to provide an improved strap stretching device comprising gripping devices adapted to engage a flexible binder passed around a package 10 or the like, such as a flat flexible steel strap, and including means for automatically effecting the release of the gripping devices from the binder after it has been drawn taut. Another object of the invention is to provide an improved strap 15 stretching device comprising relatively movable gripping devices adapted to engage a flexible binder passed around a package or the like and comprising operating mechanism for drawing the strap taut in combination with means adapted to be actuated by said operating mechanism for releasing one of said gripping devices from the binder. Still another object of the invention is to provide an improved strap stretching device comprising a gripping member normally actuated by 20 resilient means to engage a flexible binding strap or the like, in combination with other means adapted to be energized by the operating mechanism of the device for causing the gripping member to be released from the strap after the strap 25 has been drawn taut. Still another object of the invention is to provide an improved strap stretching device comprising relatively movable members each carrying a gripping device adapted to engage one end of a flexible binder or the like drawn around a package in combination with operating mechanism for effecting relative movement of said members to draw the strap taut and resilient means actuated by said operating mechanism for causing one of said gripping devices to 30 become disengaged from said strap upon a predetermined movement of said operating mechanism. Other objects relate to various features of construction and arrangement which will appear more fully hereinafter.

45 The nature of the invention will be understood from the following specification taken with the accompanying drawings, in which one embodiment is illustrated. In the drawings,

50 Fig. 1 shows a side elevation of the improved strap stretching device seated on the surface of a box or package and engaging a flexible binder which has been drawn taut around the box or package;

55 Fig. 2 shows a top plan view of the structure illustrated in Fig. 1;

Fig. 3 is a sectional view taken on the line 3—3 of Fig. 1;

Fig. 4 is a perspective view of the lower end of the operating lever of the strap stretching device, showing the cam which operates to actuate the 5 resilient means by which one of the gripping devices is released from the strap;

Fig. 5 is a perspective view of a pawl carried by the operating lever and of an adjacent stationary cam adapted to actuate the pawl to disengage it 10 from the ratchet wheel when the lever reaches a predetermined position;

Fig. 6 is an enlarged horizontal section taken on the lines 6—6 of Figs. 1 and 8;

Fig. 7 is a vertical section taken on the line 7—7 15 of Fig. 6;

Fig. 8 is a longitudinal vertical section taken on the line 8—8 of Fig. 6 with the operating lever in the position shown in Fig. 1, wherein the pawl engages the ratchet wheel;

Fig. 9 shows a side elevation of the right-hand portion of the strap stretching device illustrated in Fig. 1, with a partial vertical section on the line 8—8 of Fig. 6; and

Fig. 10 shows an enlarged horizontal section 25 taken on the line 10—10 of Fig. 9.

As illustrated in the drawings, the improved strap stretching device 15 is shown as being mounted on the top surface of a box or package 16 about which there is passed a flat flexible steel 30 strap 17 which has been drawn taut preliminary to securing the overlapping ends 17^a and 17^b thereof together by means of a seal joint 18. This joint may be of various forms but may preferably be of the form disclosed in the United States 35 patent of Ralph H. Norton No. 1,260,016, dated March 19, 1918.

The sealing device 15 comprises a block 20 which rests upon the surface of the package 16 and which has a longitudinal slot 20^a extending 40 therethrough to be closely fitted by the end of a rack bar 21. This rack bar is secured in rigid relation to the block 20 by a cap screw 22 extending through the bar and the lower walls of the slot and having a threaded engagement with 45 the lower wall, as shown in Fig. 3. The block 20 has a forwardly extending flange 20^b adapted to be engaged on its upper side by the end portion 17^a of the strap 17 and this flange is beveled downwardly toward the end of the package 16 50, to facilitate the passage of a strap thereover. The strap 17 is held in engagement with the flange 20^b by a gripping dog 23 which is rotatably mounted upon a pin 24 secured in an aperture 20^c formed in the block 20. The pin 24 is held in 55

place by a vertically extending pin 25 passing downwardly through the block 28 and through a groove formed in one side of the pin 24. The pin 24 is provided at its outer end with an enlarged head or flange 24^a which overlies the hub portion 28^a of a handle 26, formed of bronze or the like, which is engaged by the pin 24 and which has a fixed relation to the gripping dog 23 through the coaction of its lower horizontal edge 28^b with the shoulder 23^b formed on the gripping dog. The gripping dog is provided with a lower serrated gripping surface 23^c which is adapted to engage and bite into the upper surface of the strap 17 and this gripping surface is offset toward the right from a plane passing through the axis of the pin 24, as viewed in Fig. 1, so that a pull upon the strap 17 toward the left tends to increase the grip of the dog upon the strap while relative movement of the strap 17 and gripping dog in the opposite direction tends to release the strap. The gripping dog 23 is provided with a cylindrical bore 23^d in which is mounted a pin or plunger 27 adapted to be pressed against a flange 28^d on the block 28 by a coil spring 28 which is mounted in the inner end of the bore. The pin 27 and spring 28 thus tend normally to maintain the dog 23 in a position to grip the strap 17, as shown in Fig. 1, but by pressing downwardly upon the handle 26, the gripping dog may be rotated against the compression of the spring 28 to raise the serrated gripping surface 23^c away from the strap. This gripping dog may be of the form described and claimed in the United States patent of John Eker Ott No. 1,809,566, granted June 9, 1931.

The rack bar 21 is provided on its upper side, throughout a considerable portion of its length, with rack teeth 21^a and this portion of the bar is slidably engaged by a hollow-block or housing 38 having rectangular apertures 38^a and 38^b in the end walls thereof which are slidably engaged by the rack bar, as shown in Fig. 8. The block 38 is provided with a forwardly extending flange 38^c at its lower edge which is adapted to be engaged on its upper side by the end portion 17^b of the strap 17 and this flange is also beveled on its upper side toward the adjacent end of the package to facilitate the passage of the strap thereover. The strap 17 is adapted to be held in engagement with the flange 38^c by a gripping dog 33 which is rotatably mounted upon a pin 34 secured in a bore 38^d formed in the block, as shown in Fig. 7, and the pin 34 is adapted to be held in this position by a vertically extending pin 35 passing downwardly through the block and a groove formed in the lateral side of the pin 34. This pin 34 has an enlarged head 34^a which overlies the front face of the gripping dog 33 and the gripping dog is provided on its under side with a serrated gripping surface 33^c which is adapted to engage and bite into the metal of the strap 17 on its upper side. As viewed in Fig. 1, the serrated gripping surface 33^c is offset toward the left on a vertical plane passing through the axis of the pin 34 so that a pull upon the strap 17 toward the right will tend to increase the grip of the dog upon the strap while movement of the strap in the opposite direction with respect to the gripping dog will release the dog from the strap. This gripping dog 33 is normally held in strap-engaging position by a pin or plunger 37 which slidably engages a bore 33^d formed in the gripping dog and which is pressed against a flange 38^e on the block or housing 38 by means of a coil spring 37^a mounted in the inner end of the bore, as

shown particularly in Fig. 10. Assuming that the seal joint 18 has not been formed and that the strap 17 has been passed around the package and the end portions 17^a and 17^b thereof put in place beneath the gripping dogs 23 and 33, respectively, it will be apparent that relative movement of the two blocks 28 and 38 toward each other will draw the strap taut around the package with the ends thereof between the blocks in overlapping relation so that when the strap has been brought to the required degree of tautness, the seal may be applied to form the interlocking joint.

For the purpose of effecting relative movement of the blocks 28 and 38, a gear wheel 38 is arranged to mesh permanently with the rack teeth 21^a, as shown in Figs. 7 and 8, and this gear wheel is rotatably mounted upon a bolt or pin 39 upon which there is pivoted an operating lever 40 having a spherical handle 40^a at the outer end thereof. As shown in Fig. 6, the bolt 39 engages apertures formed in bosses or hubs which constitute parts of the side walls 38^f and 38^g of the block or housing 38, the bolt having an enlarged head 39^a at one end which is flattened at one side as shown at 39^b to engage the adjacent vertical shoulder 38^h on the block to prevent rotation of the bolt. At the other end, the bolt is provided with a threaded portion engaged by a nut 41. The gear wheel 38 is located in the chamber 38ⁱ between the side walls of the block or housing and it is embraced on opposite sides by the flanges 40^b which are formed on the lower end of the operating lever 40 and which are pivotally engaged by the bolt or pin 39. The gear wheel 38 is rotated upon reciprocation of the lever 40 through the agency of a pawl 42 which is of cylindrical form as shown in Fig. 5, comprising a body portion 42^a and a projecting end portion 42^b of reduced diameter. The body portion 42^a is journaled in apertures which are formed in the side flanges 40^b of the operating lever and the part between the side flanges is milled off to form a slot 42^c having a flat inner face 42^d and teeth 42^e at its opposite edges. The body portion 42^a projects beyond one side flange 40^b of the operating lever and this part is milled off to form another flat face 42^f which, when the lever 40 reaches a predetermined position in its angular movement toward the right, as viewed in Fig. 1, engages a cam face 38^j formed on the side wall 38^g of the block 38 with the result that the pawl 42 is rotated to release from engagement with the teeth of the gear wheel 38 the tooth 42^e of the pawl which has previously been in engagement therewith, thus permitting the gear wheel to pass freely through the notch 42^c of the pawl. The pawl 42 is normally turned to a position wherein the tooth 42^e engages the teeth of the ratchet wheel to cause rotation of the ratchet wheel, upon movement of the lever 40 toward the left as viewed in Fig. 1, by the action of a coil spring 44 which is mounted around the reduced extremity 42^b of the pawl with one end thereof passing through a transverse aperture 42^g formed in this part of the pawl and with the other end thereof bearing against a lug 40^c which is provided on one of the side flanges 40^b of the operating lever, as shown in Fig. 4. When the lever 40 is moved toward the left, as viewed in Fig. 1, the tooth 42^e of the pawl engages a tooth of the gear wheel 38, as shown in Fig. 8, with the result that the gear wheel is rotated and the block 38 moves toward the left along the rack bar. Upon reverse movement of the lever 40, the flat face 42^f of

the pawl slides over the gear teeth so that the gear remains stationary while the lever is retracted to a new starting position.

During this reverse motion of the lever 40, the block 30 is held stationary with respect to the rack bar 21 by one or the other of two detents 45 which are pivotally mounted upon a bolt or pin 46 extending through the side walls 30^a and 30^b of the block or housing, as shown in Figs. 6 and 8. This bolt 46 has an enlarged head 46^a at one end which overlies the side wall 30^b of the housing and which is preferably set into a circular recess in the housing. At the other end, the pin or bolt is threaded for engagement by a nut 47. The detents 45 are provided with teeth 45^a which are adapted to enter the recess between the rack teeth 21^a and these teeth 45^a of the detents are offset from each other longitudinally of the rack bar, as shown in Fig. 8, so that they engage alternate spaces along the rack bar, one detent resting upon the top of one tooth when the other detent is engaging a recess between that tooth and the next adjacent tooth. These detents are normally forced into engagement with the rack bar teeth by a pair of coil springs 48 which engage sockets 45^b formed in the detents at one end and which have their other ends arranged to contact with an overhanging flange 30^c formed on the end wall of the block 30. These detents are provided with arms 45^c extending from the pin or bolt 46 toward the axis of the gear wheel 38 and when the operating lever 40 is swung to an extreme position toward the right, as shown in Fig. 9, these arms 45^c are engaged by a bar 40^d extending between the side flanges 40^b of the operating lever with the result that the detents are elevated against the compression of the springs 48 out of engagement with the teeth of the rack bar, thereby permitting the block or housing 30 to move freely along the rack bar except for such resistance as may be provided by the resistance of the gripping dog 33 with the strap 17 if the gripping dog is then in engagement with the strap. The flange 30^c of the block or housing is provided with a notch 30^d which is adapted to receive the lower edge of the operating lever 40 when it is in its lowermost right-hand position, as shown in Fig. 9. The extent to which the block 30 may move toward the right along the rack bar 21, as viewed in Fig. 1, is limited by a pin or stop member 49 extending upwardly from the rack bar adjacent the right-hand end thereof, as shown in Fig. 1, and to facilitate the handling of the device in placing it upon or removing it from a package, this end of the rack bar is provided with a mushroom-shape handle 50 secured to the rack bar in an inclined position by means of a screw 51.

For the purpose of causing the automatic release of the gripping dog 33 from the strap 17 after the strap has been drawn taut and the joint 18 formed, the strap stretching device is provided with means for moving the gripping dog from the gripping position shown in Fig. 1 when the lever 40 has been removed to the extreme right-hand position shown in Fig. 9 to release the detents 45 from the rack bar. The block 30 is provided with an inclined passage 30^m in which is mounted a coil spring 52 of greater strength than the spring 37^a by which the plunger 37, mounted in the detent, is forced against the flange 30^c. The spring 52 is engaged at one end by a spherical ball 53 which is adapted to press against an upright shoulder 33^d formed on the gripping dog 33, as shown in Fig. 10, and at its

other end, the spring 52 bears against another spherical ball 54 which is adapted to be engaged by the face of a cam 55 formed on the adjacent side flange 40^b of the operating lever 40. The cam 55 occupies a recess 30ⁿ formed in the side wall 30^b of the block or housing 30 and when the operating lever 40 reaches the position shown by dotted lines in Fig. 9, the cam 55 engages the ball 54 and moves it downwardly in the passage 30^m with the result that the spring 52 is compressed and the lower ball 53 is caused to exert a pressure upon the gripping dog 33 tending to turn it in a clockwise direction as viewed in Fig. 9. Owing to the resistance provided by the bite of the teeth of the serrated portion 33^c of the gripping dog into the metal of the strap 17, this pressure of the ball 53 upon the gripping dog will not immediately release the gripping dog from the strap but when the operating lever 40 reaches its extreme right-hand position, shown by full lines in Fig. 9, the pawls 45 will be disengaged from the rack bar, thereby causing a slight movement or jump of the block 30 due partly to the impact of the release and partly to the expansion of the bound strap which has not been under tension in the region between the blocks 20 and 30. When this slight jump or movement of the block 30 takes place, the bite of the teeth of the gripping dog 33 in the middle of the strap will be released and the spring 52 will then overcome the spring 37^a and move the gripping dog 33 about its pivot to the position shown in Fig. 9, thereby automatically releasing the strap. At the same time, the operator may actuate the handle 26 at the other end of the device to release the gripping dog 23 so that the tool may then be moved sidewise to withdraw the flanges 20^b and 30^c from their positions beneath the strap. In this way, the operation of the tool by a single operator is greatly facilitated and the release of the tool from the strap may be readily effected when the seal has been drawn taut and the joint formed.

Although one form of the invention has been shown and described by way of illustration, it will be understood that it may be constructed in various other forms coming within the scope of the appended claims.

I claim:

1. The combination in a strap stretching device, of means for gripping opposite end portions of a strap, means for effecting relative movement of said gripping means to draw said strap taut around a package or the like, and means actuated by said last named means for releasing said strap from one of said gripping means.

2. The combination in a strap stretching device, of means for gripping the strap, means for moving said gripping means to tighten said strap around a package or the like, means for actuating said last named means, and means operated by said actuating means for releasing said gripping means from said strap.

3. The combination in a strap stretching device, of means for drawing a strap taut around a package and then relieving the tension thereon after the ends of the strap have been secured together, a gripping device for holding said strap while it is being drawn taut, and means operative when said tension is relieved for releasing said strap from said gripping device.

4. The combination in a strap stretching device, of a pair of relatively movable members each adapted to be secured to a strap, a gripping device carried by one of said members for gripping

5 said strap, means for effecting relative movement of said members for drawing said strap taut around a package, means for operating said last named means, and means actuated by said last named means for effecting the release of said strap from said gripping device.

6 5. The combination in a strap stretching device, of a pair of relatively movable members each 10 adapted to be secured to one end portion of a strap, a gripping device carried by one of said members for gripping said strap, means for effecting relative movement of said members for drawing said strap taut around a package, means for operating said last named means, and means actuated by said last named means for storing up energy to effect the 15 release of said strap by said gripping device after said strap has been drawn taut.

20 6. The combination in a strap stretching device, of a pair of relatively movable members, means for securing one end portion of a strap to one of said members, a gripping device carried by the other of said members for gripping another portion of said strap, means for effecting relative movement of said members to draw said strap taut 25 around a package or the like, means for operating said last named means, and a spring adapted to be actuated by said operating means for releasing said gripping device from said strap after said strap has been drawn taut.

25 7. The combination in a strap stretching device, of a pair of relatively movable members, means for securing one end portion of a strap to one of said members, a gripping device carried by the other of said members for gripping another portion of said strap, means for effecting relative movement of said members to draw said strap taut around a package or the like, means for operating said last named means, means tending to maintain said gripping device in engagement with said strap, and means adapted to be actuated by said operating means when said strap 30 has been drawn taut for overcoming said last named means to release said strap from said gripping device.

35 8. The combination in a strap stretching device, of a pair of relatively movable members, means for securing one end portion of a strap to one of said members, a gripping device carried by the other of said members for gripping another portion of said strap, means for effecting relative movement of said members to draw said strap taut around a package or the like, means for operating said last named means, means including a spring for normally maintaining said gripping device in engagement with said strap, and a second spring adapted when compressed to overcome said first-named spring to release said strap from said gripping device, said last-named spring being adapted to be compressed by said operating means after said strap has been drawn taut.

40 9. The combination in a strap stretching device, of a pair of relatively movable members each adapted to be secured to one end portion of a strap, a gripping device for securing one of said members to said strap, means including a reciprocating handle for effecting relative movement of said members to draw said strap taut around a package or the like, a cam actuated by said han-

5 dle, and means operated by said cam for causing said gripping device to release said strap upon a predetermined movement of said handle.

10 10. The combination in a strap stretching device, of a pair of relatively movable members each 10 adapted to be secured to one end portion of a strap, a gripping device for securing one of said members to said strap, means including a reciprocating handle for effecting relative movement of said members to draw said strap taut around a package or the like, a cam actuated by said handle, a spring adapted to be compressed by a predetermined movement of said cam, and means actuated by said spring for releasing said gripping device from said strap.

15 11. The combination in a strap stretching device, of a pair of relatively movable members each adapted to be secured to one end portion of a strap, a gripping device for securing one of said members to said strap, means including a 20 reciprocating handle for effecting relative movement of said members to draw said strap taut around a package or the like, a cam actuated by said handle, a spring adapted to be compressed by a predetermined movement of said cam, means 25 actuated by said spring for releasing said gripping device from said strap, and a second spring of lesser strength than said first named spring engaging said gripping device and tending to maintain said gripping device in engagement with said strap, said gripping device having a serrated gripping surface adapted to engage said strap.

30 12. The combination in a strap stretching device, of a pair of relatively movable members each adapted to be secured to a strap passed 35 around a package or the like, said members being adapted by relative movement toward each other to draw said strap taut with its ends overlapping in the region between said members, a pair of gripping devices for securing said strap to said members, a spring engaging one of said members and one of said gripping devices for maintaining that gripping device normally in engagement with said strap, said last named member having a passage therein adjacent said last mentioned gripping device, a spring mounted in said passage, means comprising a reciprocating lever for effecting relative movement of said members, and means actuated by said lever when it reaches a predetermined position for compressing said 40 last named spring, said last mentioned gripping device having a serrated gripping surface.

45 13. The combination in a strap stretching device, of a pair of relatively movable members each adapted to be secured to one end portion of a strap passed around a package, a gripping device for securing one of said members to said strap, means comprising a rack bar and a meshing gear for effecting relative movement of said members, means including a reciprocating lever 50 for rotating said gear, a detent for normally holding said gear against reverse rotation, means including a spring adapted when compressed to release said gripping device from said strap, and means actuated upon a predetermined movement 55 of said lever for releasing said gear from said detent and compressing said spring.

60 WILLIAM C. CHILDRESS.
